United States Patent Office.

R. A. CAMERON, OF VALPARAISO, INDIANA.

Letters Patent No. 68,042, dated August 27, 1867.

HEMORRHOIDIAN.

The Schedule referred to in these Letters Patent and making part of the same.

TO ALL WHOM IT MAY CONCERN:

Be it known that I, R. A. CAMERON, of Valparaiso, in the county of Porter, and State of Indiana, have invented a new and useful Improvement in Hemorrhoidian; and I do hereby declare that the following is a full, clear, and exact description of the construction and operation of the same, reference being had to the annexed drawings, and letters of reference marked thereon, making a part of this specification, in which—

Figure 1 is an elevation of my invention.

Figure 2, a sectional elevation of the ellipsoidal bulb for receiving the cold water and discharging that which is warm.

The nature of my invention consists in constructing an ellipsoidal vessel, having a suitable protuberance at one end for passing into the rectum, and collars opening into the bulb at such points at the other end as will allow cold or ice-water to enter the bulb through one collar by means of a pipe, and be discharged through the other pipe by means of the opening or collar when the water becomes too warm to answer the purpose desired; the device being operated by means of suitable valves placed in proper positions in the pipes, and the common rubber bulb used as a pump for elevating water and liquids for medical and other purposes.

The importance of my invention will be better understood when it is known that the application of cold water, or its equivalent, is now considered very important in the cure of hemorrhoids and other diseases of the rectum; and as there has been no convenient means of applying such a remedy to the affected parts, I claim that my invention is of great importance, from the fact that it obviates the use of wet cloths, which have to be frequently changed in order to produce a satisfactory result, and otherwise attended with great inconveniences, such as wetting the under-clothing of the patient, bed-clothes, &c., which is both unpleasant and dangerous. Another important advantage is gained by the use of my device, which consists in the use of a continuous flow of water into the bulb, of such a temperature as the nature of the disease requires, and at the place where local treatment is necessary; thus applying the remedy directly to the parts affected. And, further, the patient possessing ordinary strength, can apply the device without the assistance of others, which is important in the treatment of patients such as females and others possessing unusual delicacy; and in the use of the protuberance, which may be inserted in the rectum such a distance as to apply the remedy more successfully than by the common method of using ice or hip-baths to the affected parts, which is both expensive, painful, and annoying, from the fact that a considerable portion of the non-affected parts must necessarily be subject to the same treatment as the parts affected.

A shows the ellipsoidal bulb, having the protuberance B for passing into the rectum, as seen at fig. 1; and the collar D for attaching the cylinder E to the bulb A, and the injecting pipe X, attached to same cylinder. The discharge pipe W is attached to the collar C in the usual manner, and carries off the warm water from bulb A. I make the bulb A of any suitable metal not liable to corrode, the mechanical construction being similar to that of making hollow spheres. The cylinder E is fitted on to the collar D, and has, on the inside, a common check-valve for keeping the water in the bulb A. The injecting pipe X has its lower end connected with the receiving pipe J by means of the cylinder H and the collar S, said receiving pipe being attached at the upper end to the common flexible pump K, used for elevating the water, and at the lower end to the cylindrical box I, which has, on the inside, a suitable check-valve. I make the pipes W X J of rubber, and of such a length as is most convenient for use.

Operation.

The protuberance B must be inserted in the rectum, and the lower end of pipe J placed in the water to be forced into bulb A, after which the pump K can be worked in the usual manner, and the surplus water will be discharged through the pipe W.

Having thus described my invention, what I claim, and desire to secure by Letters Patent, is—

The ellipsoidal bulb A, having the protuberance B, when constructed and operated substantially as and for the purpose set forth.

R. A. CAMERON.
